COUPLING ARRANGEMENT

Henri G. Busignies, Forest Hills, Trevor H. Clark, New York, and Arbor G. Everhart, Islip, N. Y., assignors to Federal Telephone and Radio Corporation, Newark, N. J., a corporation of Delaware

Application August 26, 1943, Serial No. 500,076

4 Claims.

1

This invention relates to coupling arrangements and in particular to circuit arrangements for coupling a plurality of receivers to a low impedance transmission line.

Among the objects of our invention are:

To provide an effective coupling circuit for use such as between a low impedance transmission line and a radio receiver.

To provide between a low impedance transmission line and a receiver a coupling means having characteristics such that the effect of the receiver on the transmission line is substantially nil.

To provide between a low impedance transmission line and a receiver a coupling means in which the reaction from its output to its input circuit is substantially balanced.

To provide a plurality of coupling means between a low impedance transmission line and a plurality of receivers which will substantially prevent inter-action between the receivers.

To provide between a radio direction finding system and a plurality of receivers a coupling means having characteristics such that there is substantially no inter-action between the receivers and the direction finding system.

These and other objects of our invention will best be understood by the following description of a preferred embodiment thereof, described for purposes of illustration and shown in the accompanying drawing.

In the drawing we have represented by reference numeral 2 a directive antenna system of the Adcock type having four monopole antennas 4, 6, 8, and 10 positioned on the corners of a square in a usual manner. A monopole sensing antenna 12 is positioned in the geometrical center of the square. Between the monopoles and ground are antenna coupling units 14, 16, 18, 20 and 22. These coupling units may be of the type described in a copending Busignies application Serial Number 481,760 filed April 3, 1943, now Patent No. 2,434,904 granted January 27, 1948 and comprise vacuum tube amplifiers of the cathode follower type. As described in said copending application these coupling units have an input impedance suitable for matching the impedance of the antennas to which they are connected and a relatively low output impedance suitable for matching the impedance of a low impedance transmission line to which the output of said coupling unit is connected.

In accordance with the teaching of a copending Busignies application Serial No. 445,468 filed June 2, 1942, now Patent No. 2,424,968 granted August

(Cl. 250—9)

2

5, 1947, transmission lines represented by reference numerals 24, 26 extend from the coupling units 14 and 18 and at right angles to the plane of the antennas 4 and 8. These transmission lines are cross connected at the point 28 where they connect with a further transmission line 30 which extends to a direction finding receiver 32 located at a distant point. The characteristics of these transmission lines are such that a suitable impedance match occurs at the point 28. In the drawing we have schematically represented these transmission lines as a single conductor. However, these lines may be of any suitable type for example they may be unbalanced coaxial lines or balanced lines, either type of which is well known in the art.

Similarly, we have shown transmission lines 34, 36 extending from coupling units 16 and 20 respectively and at right angles to the plane of the antennas 6 and 10. These transmission lines are cross connected at the point 38 where they connect to the transmission line 40, the latter also extending to the direction finder receiver 32. As described in copending application 445,468 this construction of transmission lines in the vicinity of the antenna system is for the purpose of reducing polarization effects.

From the coupling unit 22 connected with sensing antenna 12 there is a balanced transmission line comprising conductors 42 and 44 also extending to the direction finder receiver. This balanced line could also be an unbalanced coaxial line but for the purpose of this description we have illustrated a line of the balanced type in order to illustrate certain features of our invention.

The direction finder receiver may be of the type and comprise the units described in a Busignies and Richardson application Serial Number 400,154 filed April 23, 1942, now abandoned. The specific construction of the direction finder receiver constitutes no part of our present invention.

In any direction finding system of the type illustrated in which low impedance transmission lines extend between the antenna system and the receiver it has heretofore been considered undesirable to connect any apparatus to these lines because of the probability of destroying the accuracy of the direction indications. It would be very useful and advantageous however if, in connection with a direction finding system, other reception means could be employed. However, other antennas located in the vicinity of the direction finding antenna system might prove

harmful in that they might have an undesirable influence on the otherwise symmetric field pattern of the direction finding antenna system.

We have discovered that by employing between a transmission line and a receiver a coupling arrangement having certain desirable properties in accordance with our invention, it is possible to connect either a single receiver or a plurality of receivers to the transmission lines of a direction finding system without upsetting the balance or in any other way destroying the accuracy of the direction indications. In the drawing, the coupling arrangement comprises the vacuum tube amplifier shown within the dotted block 46. The amplifier comprises a vacuum tube 48 having cathode, control grid, and plate electrodes, 50, 52 and 54 respectively and also a screen grid 56 and a suppressor grid 58. Between the cathode and ground and between the anode and ground there are resistors 60 and 62 respectively. Resistor 60 is in the input circuit of the amplifier while both resistors 60 and 62 are in the output circuit thereof. Capacitor 64 serves as a coupling between the amplifier and the conductor 44 of the transmission line between the sensing antenna and the direction finder receiver. Resistor 66 is a grid leak. A positive potential is applied to the anode 54 and also to the screen grid 56, the potential to the latter being supplied through resistor 68. Capacitors 70 and 71 by-pass radio frequency currents to ground. Capacitors 72 and 74 serve as coupling reactors between the output of the amplifier and the receiver 76. The receiver 76 may be of any known type capable of being tuned to any frequency in a wide frequency band. It will be noticed that there are no tuning elements between the receiver 76 and the antenna 12 with which it is associated, all circuits between said antenna and said receiver being of an aperiodic character.

Due to the character of the amplifier circuit which splits the phase of an input voltage and produces two output voltages, one positive and one negative with respect to ground, the reaction between the output and input circuits is very small. For example, if a positive potential with respect to ground appears on control grid 52, a positive potential also appears in the output circuit between the resistor 60 and the cathode 50. However, a negative potential with respect to ground appears in the output circuit between the resistor 62 and the anode 54. These positive and negative potentials tend to neutralize each other in their reaction on the control grid 52 in the input circuit. These positive and negative potentials are also coupled to and actuate receiver 76 through the coupling capacitors 74 and 72 respectively.

The neutralization from the output to the input circuit may be made substantially complete by connecting two neutralizing capacitors 80 and 82 between the plate and control grid and between the cathode and control grid respectively. The rotor plates of these capacitors may be mounted on a common shaft and so positioned with respect to their corresponding stator plates that, as the capacitance of one capacitor increases the capacitance of the other capacitor decreases. By suitable adjustment of the neutralizing capacitors the effective capacitances between the control grid 52 and the plate and between the control grid and the cathode may be made substantially equal thus preventing the transmission of high frequency energy through the tube due to capacitance effects. If it is known which

of the tube interelectrode capacitances is the smaller, a single neutralizing capacitor may be connected in parallel with the smaller interelectrode capacitance.

The input impedance of the amplifier is relatively high, preferably of the order of 5000 ohms or more. This impedance connected between the conductor 44 of the transmission line and ground is so high that it practically has no influence on the relatively low impedance of the transmission line and, therefore, produces substantially no unbalance of the latter.

In the drawing we have also shown a plurality of other receivers and coupling units connected to the low impedance lines 42, 44. These receivers and coupling units may be identical to the receiver 76 and coupling unit 46 described above. The input impedance of all of the coupling units in parallel is still relatively very high with respect to the low impedance of the transmission line which may be of the order of 125 to 140 ohms. Therefore even though a plurality of receivers are connected to the transmission line, there is still substantially no deleterious reaction. We have shown a plurality of receivers, specifically three, coupled to the conductor 44 and a like plurality of receivers coupled to the conductor 42. In this manner any minor unbalance which might possibly occur on one conductor is compensated for by a similar unbalance on the other conductor. It is to be understood, however, that even if there were an unequal number of receivers coupled to the two conductors of the balanced transmission line 42—44, any unbalance of the line would be so small as to have a substantially negligible effect. For the reasons above described whereby the reaction between the output and input circuits of the coupling unit is very small, there is also substantially no reaction between any two receivers of a plurality of receivers connected to the transmission lines. This is true even though the various receivers are tuned to the same frequency. In such a case any reaction which does occur is more likely to be due to other causes such as extraneous coupling rather than to the fact that the receivers are coupled to a common transmission line.

In the drawing we have illustrated the receivers as connected to the line between the sensing antenna and the direction finder receiver. This is preferable because of symmetry but the receivers could also be connected to lines extending from the outer monopoles to the direction finder receiver. Furthermore the direction finding antenna system could comprise dipole rather than monopole antennas.

While we have described above the principle of our invention in connection with specific apparatus, it is to be clearly understood that this description is made by way of example and not as a limitation on the scope of our invention as set forth in the objects thereof and the accompanying claims.

We claim:

1. In combination, a direction finding system comprising an aperiodic directional antenna system and an aperiodic non-directional antenna system, a direction finding receiver, a pair of low impedance transmission lines each coupled at one of their ends to separate of said antenna systems, and terminating at their other ends at said direction finding receiver and coupled thereto, an even number of additional receivers, and a like number of coupling units, half of said coupling units coupling half of said receivers to one conductor of one

of said transmission lines and the other half of said coupling units coupling the other half of said receivers to the other conductor of said one transmission line, whereby any interaction of one of said receivers with one of the transmission lines is balanced by a like interaction of one of the receivers coupled to the other of the transmission lines, with said other of the transmission lines.

2. The combination according to claim 1 wherein each of said coupling units have a high impedance relative to the impedance of the transmission lines.

3. The combination according to claim 1 wherein each of said coupling units comprises a vacuum tube amplifier having cathode, control grid and anode electrodes, an input circuit connected between said cathode and control grid, an output circuit connected between said cathode and anode, and neutralizing means connected between said output and input circuits to minimize reaction therebetween.

4. The combination recited in claim 1 wherein each of said coupling units comprises a phase splitting vacuum tube amplifier.
